UNITED STATES PATENT OFFICE.

HERMAN TRIPP AND GEORGE E. STEPHENSON, OF CHICAGO, ILLINOIS.

CHANGEABLE ELECTRIC-LIGHT SIGN.

SPECIFICATION forming part of Letters Patent No. 637,905, dated November 28, 1899.

Application filed June 19, 1899. Serial No. 721,188. (No model.)

To all whom it may concern:

Be it known that we, HERMAN TRIPP and GEORGE E. STEPHENSON, citizens of the United States, residing at Chicago, in the county of Cook and State of Illinois, have invented certain new and useful Improvements in Changeable Electric-Light Signs, of which the following is a specification.

The object of our invention is to construct an electric-light sign in which the letters can be readily and quickly changed and repairs easily made; and the invention consists in the features and combinations hereinafter described and claimed.

In the accompanying drawings, Figure 1 is a plan view of the front of the sign, showing a single letter in position; Fig. 2, a longitudinal section, on line 2 of Fig. 1, looking in the direction of the arrow; Fig. 3, an end elevation; Fig. 4, an enlarged plan view of a letter with the outer shell or covering removed, showing the conductors and arrangement of lamp-sockets; and Fig. 5, an enlarged detail in section, on line 5 of Fig. 1, looking in the direction of the arrow.

In carrying out our improvement we use a frame or backing A, made of wood, iron, or other suitable material and of the desired width and length for the sign. This frame or backing is provided with slots a, two slots being used for each line of letters, which slots may extend the full length, if desired. Conductors B and B' for the positive and negative currents are located in line with the slots and each conductor is incased by a shell or covering C, made of galvanized iron or other suitable material. Each conductor is properly insulated at the end of its shell or casing C by insulators b and suitably supported within its shell or casing by arms or standards c.

Each letter is preferably formed in a telescopic manner, having an inner shell or casing D and an outer shell or covering D' fitting over the inner shell, so that by the removal of the outer covering or shell the electric connections are accessible for repairs or other attention.

Each letter is provided with fusing-plugs, one for each conductor, each plug consisting of an inner portion E, having spring-arms e, which clamp around or over the conductor to

furnish contact, and an outer portion F, carrying a fusible material, which portion can be in the form of a screw-threaded plug or 55 a push-plug or other suitable construction which can be entered through the outer shell or cover and be engaged with the inner portion of the fuse to furnish the contact for the circuit.

Each letter is provided with the requisite number of electric sockets G for the reception of incandescent lights H. The shape of the shell or casing conforms to the shape of the letter desired, and each letter is provided 65 with the requisite number of electric sockets to give the desired outline for the letter through the incandescent lights. Each letter has within the inner shell or casing the wiring d, running from socket to socket, and a connection f, running from the fusing-plug to a 70 socket, so as to complete the circuit when the two parts of the fusing-plug are in contact.

Each letter is provided with individual fuses so constructed or arranged that each 75 letter has control of its own current and is independently accessible in case of any defect in the current or otherwise, so as to enable repairs to be made, all that is necessary being to break the contact of the fuse by 80 withdrawing the outer portion thereof, which shuts off the current to the lights. The fusing-plugs also act as a safeguard in case of an excess of current or any short-circuiting, which would produce a high voltage that 85 would cause injurious effects, as any increase of the voltage over the amount which the fusing material would stand at once destroys the fuse and breaks the circuit, shutting off the current from the letter.

The contacts formed with the clamp portion enable a ready changing of the letters to be made, as a letter can be removed from its place by taking hold of the shell or casing and pulling or withdrawing the clamp from 95 the conductors and removing the letter. This enables the letters to be readily changed and the same board to be employed for different signs, as desired.

While we have described our invention with 100 more or less minuteness as regards details, we do not desire to be limited thereto unduly any more than is pointed out in the claims. On the contrary, we contemplate changes in

form, construction, and arrangement, the omission of parts, and use of equivalents as circumstances may suggest or render expedient.

5. We claim—

1. In an electric-light sign, the combination of a backing consisting of sections provided with slots, conductors in line with the slots, and letters provided with contacts passing through the slots and securing the letters to the backing and conductors, substantially as described.

2. In an electric-light sign, the combination of a slotted backing, conductors in line with the slots of the backing, a casing for each conductor, and removable letters having contacts clamping the letters to the conductors and backing, substantially as described.

3. In an electric-light sign, the combination of a letter, a fuse individual to the letter, and an inner or rearward extension from the fuse terminating in a clamp to engage with an electric conductor and attach the letter to the conductor and complete an electric circuit by the placing of the letter in position, substantially as described.

4. In an electric-light-sign letter, the combination of a casing having a bottom and side walls forming the contour or outline of the desired letter, a series of sockets attached to the bottom and projecting to the plane of the front of the casing and adapted to receive in the projected ends incandescent electric lights, a fuse for the negative and a fuse for the positive current, the outer end of each fuse projecting beyond the plane of the front of the casing, a system of wiring within the casing connecting the sockets and fuses, an inner or rearward extension from each fuse terminating in a clamp to engage with an electric conductor for the clamp to attach the letter in place and complete an electric circuit for the series of incandescent lights of the letter, and a cover for the front of the

casing having holes for the projecting ends 45 of the sockets and fuses, substantially as described.

5. In an electric-light sign, the combination of a slotted back, a positive and negative conductor at the rear of the back, detachable 50 letters for the front of the back, each letter having a positive and negative contact, each contact adapted to pass through a slot and furnish the means for securing the letter in place and each contact extending from a fuse 55 in the letter, whereby the engagement of the contacts with the conductors completes an independent electric circuit for each letter enabling each letter to be independently removable without disarrangement of the circuit of the remaining letters, substantially as described.

6. In an electric-light sign, the combination of a letter having a positive and negative fuse and a rearward extension of each fuse 65 constituting a means for connecting the letter to the conductors and at the same time securing and holding the letter in position, and a slotted back receiving on the front the letter for the rearward extensions of the fuse 70 to pass through the slots of the back and hold the letter in place by the attachment of the fuse extensions to the conductors, substantially as described.

7. In an electric-light sign, the combination 75 of a letter, a positive and a negative fuse individual to the letter, an inner or rearward extension of each fuse, and spring-arms for each extension furnishing a clamp for attachment of the letter to the conductors and 80 completing an electric circuit for the letter by the act of securing the letter in place, substantially as described.

HERMAN TRIPP.
